UNITED STATES PATENT OFFICE.

ABRAM C. MOTT, OF PHILADELPHIA, PENNSYLVANIA.

DESIGN FOR A BOILER-SECTION FOR FURNACES.

SPECIFICATION forming part of Design No. 26,996, dated April 27, 1897.

Application filed March 20, 1897. Serial No. 628,541. Term of patent 14 years.

To all whom it may concern:

Be it known that I, ABRAM C. MOTT, a citizen of the United States, residing in Philadelphia, Pennsylvania, have invented a certain new and useful Design for a Boiler-Section, of which the following is a specification.

My design for a boiler-section of a steam or hot-water furnace is fully illustrated in the accompanying drawings, in which—

10 Figure 1 illustrates the boiler-section in perspective; and Fig. 2 is a sectional view on the line 2 2, Fig. 1.

15 The essential feature of the design is the L-shaped section with a depending rib and side ribs.

A is the main body of the section, having depressions *a* at each side, forming a hollow web *b*, and extending from each side of the

20 web is a rib *c*, and depending from the back of the section A is a leg-section B, terminating in a circular projection *b'*, and extending down from the under side of the section A is a tongue *d*, which is connected to the back leg B.

I claim—

25 The design for a boiler-section of a steam or water heating furnace substantially as herein described and as shown in the accompanying drawings.

In testimony whereof I have signed my name to this specification in the presence of two subscribing witnesses.

ABRAM C. MOTT.

Witnesses:

WILL. A. BARR,
JOS. H. KLEIN.
